PASQUALE T. GABRIEL, OF BROOKLYN, NEW YORK, ASSIGNOR TO DOMINICK LA VALLE, OF NEW YORK, N. Y.

WOODEN HEEL

Application filed December 6, 1928. Serial No. 324,105.

This invention relates to an improvement in wooden heels, and has for an object the provision of a construction whereby wooden heels of the so-called Cuban type may have 5 their height increased appreciably in excess of that now practicable, without spoiling the lines thereof.

Prior to this invention the height of Cuban heels has been limited owing to the tendency 10 of the heel to separate from the shoe, but the present invention overcomes this defect in a simple manner, and as mentioned above without destroying or altering in any way the lines of the heel.

15 Briefly I provide a construction in which the upper face of the heel is extended forwardly so as to overhang the heel breast, this forwardly extending portion of the heel top, however, being cut back from the heel sides 20 so that when the heel is in place upon a shoe the overhang or lip is invisible. In this way I have all the advantages of a forward extension on the heel overhanging the heel breast for preventing separation of the heel 25 from the shoe without in any way altering the lines or appearance of the heel when in use, this extension or projection of or from the heel permitting of the heel height being increased.

30 In the drawings accompanying this application,

Fig. 1 shows a shoe with my improved heel applied thereto;

Fig. 2 is a view in perspective of the heel 35 itself;

Fig. 3 is a section on the line 3—3 of Fig. 2; and

Fig. 4 is a front elevation of the heel.

Referring to the drawings in detail, my 40 improved heel designated 1 in so far as shape and style are concerned is of the Cuban type. The upper face 2 thereof is provided with a forwardly extending portion or lip 3 overhanging the heel breast 4, this overhang or 45 lip being cut back at the sides as indicated at 5 and 6 so that when the heel is applied to a shoe as shown in Fig. 1 the lip 3 being cut away or cut back at 5 and 6 from the sides of the heel is not visible to an observer. This 50 lip or overhang by taking some of the weight

of the body will obviously reduce the possibility of accidental separation of the heel and shoe, and will permit of the height of the heel being materially increased without affecting its style or lines.

The lip 3 has been described as an integral part of the wood of the heel itself. I may vary this construction, however, by inserting or setting a plate into the upper face of the heel projecting the same forwardly to overhang the heel breast 4, retaining the cut back feature at the sides above described. In other words in such construction I could very well set a plate into the upper face of the heel, the plate being narrower than the heel 65 face and extending beyond the heel breast.

What I claim is:

1. A wooden heel having the top thereof at the upper face of the heel extended forwardly to overhang the heel breast, such extension transversely of the heel being less in width than the upper end of the heel breast.

2. A wooden heel having an extension at its upper face overhanging the heel breast 75 and of a width substantially less than the upper end of the heel breast.

3. A wooden heel having a lip integral with the heel, said lip being at the upper face of the heel overhanging the breast and of a width 80 transversely of the heel less than the upper end of the heel breast.

This specification signed this 5th day of December, 1928.
